LIMITED TRAVEL DRAFT GEAR

Ernest H. Schmidt, Cleveland Heights, Ohio, assignor to National Malleable and Steel Castings Company, Cleveland, Ohio, a corporation of Ohio

Application October 27, 1931, Serial No. 571,324

2 Claims. (Cl. 213—22)

This invention relates to draft gear appliances and more particularly to the provision of means for limiting the travel of a railway draft gear to a less amount in pull than in buff.

5 An object of the invention is to provide novel and improved appliances of this type which are of simple construction, inexpensive to manufacture, easy to assemble and disassemble, and durable in service. Another object is to provide 10 a draft gear construction wherein greater compression in buff than in pull is attained without complicating spring arrangements or occupying space otherwise available for springs. Other objects and advantages will be apparent as the description of preferred embodiments of the invention 15 proceeds.

Reference will now be had to the accompanying drawings, wherein:

Fig. 1 is a plan view, partly broken away and 20 partly in section, of one embodiment of my invention.

Fig. 2 is a side elevation, also partly in section, of the construction shown in Fig. 1, and

Fig. 3 is an enlarged section taken on the line 25 3—3 of Fig. 2 looking in the direction of the arrows.

Figs. 4 and 5 are views similar, respectively, to Figs. 1 and 2, but of a modified construction embodying my invention.

30 Fig. 6 is an enlarged section on the line 6—6 of Fig. 5.

In Figs. 1, 2 and 3 there are shown at A car sills joined at their forward ends by striking casting B and at their rearward ends by back stop casting C. A friction draft gear of suitable construction is shown as comprising a wedge or follower member 1, which telescopes into the forward end of a housing member 2. Shock absorbing or cushioning mechanism of any suitable or

40 convenient type may be interposed between said wedge and housing members, the gear here shown for purposes of illustration being of the same type as that disclosed in the pending application of Ernest H. Schmidt and Hubert L. Spence, Serial

45 No. 319,064, filed November 13, 1928, Patent No. 1,913,414, June 13, 1933. The shock absorbing mechanism of such gear includes springs 4 and 5, the relatively large spring 4 being centrally located between smaller springs 5. Forward travel

50 of wedge or follower 1 may be limited by abutment thereof against rear flanged extensions B' of the draft lugs which are shown as integral with the striking casting, while rearward movement of the housing member 2 is limited by flanged extensions 15 of the back stop casting C. A yoke 7

is shown as of the vertical type with a coupler shank 8 secured as at 9 to its forward portion for swiveling action. The rear end 7a of the yoke extends along the back of the housing member 2 for compressing the draft gear under pulling forces on the coupler; while for accommodating this portion of the yoke the back stop casting may be cut away, as shown at 10, sufficiently to permit the yoke to travel say 4" in buff, or, in other words, to provide for increased travel as compared to the usual 2½" to 2¾".

Although this increased travel is desirable in buff, since buffing shocks in practice are generally much more severe than those in pull, a lesser travel is desirable in pull. In order to limit the travel of the gear in pull, I provide slots 11 in the draft gear housing 2, the housing being suitably reinforced by inwardly extending flanges 12 at either side thereof, and at the rear ends of the slots. Into said slots 11 there extend stub keys 14 which may advantageously be secured to the sills in the manner hereafter described. When no external forces are applied to the construction the housing member 2 is in its rearmost position as shown in Fig. 1, and the keys lie in the forward ends of the slots. Reinforcing flanges 13 may be provided at the forward ends of the slots 11, as shown. It will be understood that though the reinforcing flanges 13 at the forward ends of the slots are shown in abutment with the keys, while the housing member 2 is at the same time in abutment with shoulders 15 on the back stop casting, either the shoulders or the flanges may be cut away or omitted, so that all the force is taken on the other. It is generally desirable, however, to have the back stop casting arranged to receive the severe buffing shocks, while the slots 11 may be long enough to prevent the transmission of buffing shocks to the keys.

For securing the keys to the sills, openings are 95 preferably formed in the latter to permit the keys to pass therethrough, while brackets 16 with central openings for receiving the keys are aligned with the openings in the sills and secured thereto as by rivets 17. The brackets may be conveniently cast with aligned holes in their upper and lower walls for pins 18 which pass therethrough and through corresponding openings in the keys to locate the latter. Displacement of the pins may be prevented by placing cotter pins through holes 19 in the portions of the pins which extend below the brackets.

In order to insure the necessary strength when the draft gear housing goes solid against the keys, it is desirable to extend the keys for some distance

into the housing and to correspondingly extend the flanges at the ends of the slots, as best seen in Figs. 1 and 3. To accomplish this without interfering with the springs, it is desirable to employ a spring arrangement such as that shown so that the ends of keys may lie between the springs. For this purpose the ends of the keys between the springs are shown conveniently tapered as at 14a. Their other ends may be T-shaped as at 14b, to aid in locating the keys in assembling the construction. The brackets may advantageously have shouldered portions 20 for engaging the sides of the openings in the sills so that some of the forces imposed on the brackets are transmitted directly to the sills instead of through the rivets.

It is thought that the operation of the construction will be apparent from the above description, but it may be noted that under buffing 20 forces the draft gear wedge or follower 1 is free to travel say 4" in buff, while the keys 14 prevent the housing member 2 from traveling more than the desired distance, say 2" to 2½" in pull.

It may also be pointed out that in this construction no complicated draft gear is required, the only change required in gears of known type being a different casting for the housing member 2. Moreover, the full length of the space between back stop and striking castings is available for 25 the draft gear. For instance, the gear shown is 33⅞" in length as compared with the standard length of 24⅞", while standard dimensions of the car from truck center to the face of the striking casting are retained.

35 Referring now to Figs. 4, 5 and 6, there is shown a modified construction which accomplishes generally the same results as the embodiment of Figs. 1, 2 and 3. In this modified form, the usual sills A are joined by striking casting B' and back stop casting C', while the yoke 36 is of the horizontal Farlow type. Draft gear wedge or follower 31 and housing 32 are shown, the draft gear being, for example, of the same type as hereinbefore noted and including suitable springs 40 (not shown) as illustrated in Fig. 3. The yoke has a portion 33 which engages the rear end of housing member 32 for compressing the draft gear under pulling shocks, and in order to limit said compression, or, in other words, the travel of the 45 housing 32, there are shown provided in the yoke, slots 34 adapted to receive the ends of stub keys 35 which extend into the slots and may be secured to the sills in a manner similar to that shown in Figs. 1, 2 and 3. The width of the keys is shorter than the length of the slots, at least over the portions of the keys which lie in the 50 slots, so that the desired travel of say 2½" in pull is permitted before the yoke goes solid against the keys. However, to provide a stronger anchor- 55 age for the keys, they may be widened at their outer portions, which are shown as seated in brackets 36, the latter being provided with openings of practically the same width as the enlarged portions of the keys and secured to the 60 outer sides of the sills in any suitable manner, as by rivets 37. These brackets preferably have shouldered portions 38 which abut against the sills, for purposes already indicated. The keys 65 may be secured in the brackets by pins 39, and 70 are shown as T-shaped for aiding in locating the

pins in corresponding holes in the brackets and keys.

In this type of construction the keys are located so that the rear ends of the slots in the yoke go solid against them after the desired travel in pull, say 2½". As shown, the coupler 40 acts on the yoke through the usual draft key 41, while dimension b (Fig. 4) is slightly greater than a, (the latter being, for example, 2½") so that sufficient clearance is provided to prevent the key 41 from engaging the striking casting. Said key, hence, is relieved of bending forces which would otherwise be applied at its ends. In buffing, the coupler, acting through follower or wedge 31, is free to compress the gear the desired amount, say 4". Normally, the yoke seats against the back stop casting, which, moreover, is best adapted to take buffing forces, and clearance 42 (Fig. 4) is provided between each of the keys 35 and the forward ends of the respective slots 34 in the yoke, to relieve the yoke of such forces.

It may be noted that in this construction the space available for the draft gear is not limited or reduced by the means for limiting the travel, and that no changes whatsoever are required to 100 be made in the gear itself.

Moreover, the keys 35 are easily interchangeable so that by simply substituting other keys, the travel of the gear in pull may be readily varied or provision made for wear which may occur. By making the width of the portion of the key in the bracket wider than the portion in the slot, a firm seat is always provided for keys having varying widths of slot entering portions. It will be appreciated that keys such as are shown 110 in Figs. 4, 5 and 6 could also be employed in the construction of Figs. 1, 2 and 3.

The terms and expressions which I have employed are used as terms of description and not of limitation, and I have no intention, in the use 115 of such terms and expressions, of excluding any equivalents of the features shown and described or portions thereof, but recognize that various modifications are possible within the scope of the invention claimed.

I claim:

1. In a railway car draft appliance, a draft gear including a center spring and side springs and a housing member therefor, a slot formed in the housing, a car sill, and a key secured to the 125 car sill and extending into the housing between the side springs, but terminating short of the center spring and being constructed and arranged for engaging one end of the slot to limit the travel of the housing to a less amount in pull 130 than in buff.

2. In a railway car draft appliance, a draft gear comprising a housing member including a center spring and side springs, a yoke member, a car sill member at either side of said draft gear, 135 slots formed in said sill members, and projections carried by said sill members and extending toward said housing member, said projections extending from either side toward said center spring and between side springs on the same side of the 140 gear and terminating short of said center spring, said projections being constructed and arranged to limit the longitudinal movement of said housing member relative to said sill.

ERNEST H. SCHMIDT. 145
